UNITED STATES PATENT OFFICE.

GEORGE ELI MONGEAU, OF LOWELL, MASSACHUSETTS.

OUTSOLE AND WELT STITCHING MACHINE AND GUARD THEREFOR.

Specification of Letters Patent.

Patented Jan. 30, 1917.

1,213,932.

Application filed February 13, 1915, Serial No. 8,077. Renewed December 20, 1916. Serial No. 138,129.

To all whom it may concern:

Be it known that I, GEORGE ELI MONGEAU, a citizen of the United States, residing at Lowell, in the county of Middlesex and Commonwealth of Massachusetts, have invented a certain new and useful Improvement in Outsole and Welt Stitching Machines and Guards Therefor, of which the following is a specification.

10 This invention relates to outsole and welt stitching machines and guards therefor.

The object of the guard, such as herein-after described, is to guide the work upon the table; to prevent the upper from project-15^{ing} under the table where it is likely to be pierced and scratched by the needle and awl of the sewing-machine; to prevent the toe-cap of the shoe being stitched from catching on the work-receiving end of the table; to 20 avoid risks to the fingers of the workman from the awl and needle; and to accomplish all this without fitting the sole on a last while attaching the out-sole to the welt.

In United States Patent, No. 1,112,152, 25 granted to me September 29, 1914, I have shown, described and claimed a guard for such machines, in which patent the guard is represented as pressing against the front of the work-supporting table. In the arrangement of the guard and table shown in 30 said patent the nearness of approach of the upper of the shoe to the needle-slot is limited by the thickness of the upper edge of the head of the guard although said upper edge 35 "is very thin in order not to materially increase the minimum distance of the row of stitches from the shoe upper", as stated in said patent. But in many cases, it is desirable to bring the row of stitches as near as 40 possible to the upper. I have found that this may be done without materially thinning the head of the guard and without injuriously weakening the table by letting the head of the guard into the front of the table below 45 the top of said table beyond the ends of the needle-slot and making the front of the table and the front of the guard continuous surfaces.

The invention herein described enables a 50 turned shoe to be repaired by tapping. Heretofore, it has been difficult and practically impossible to repair such a shoe except by removing the sole, turning the upper inside out, attaching a new sole just as the original 55 sole was attached and again turning the

shoe. This difficulty is due to the slightness of the projection of the sole beyond the upper in turned shoes. The guard described in said patent, in some instances, and the invention herein described in all cases, allows 60 the edge of the old sole to reach over the needle slot far enough to allow a tap to be stitched to the old sole at a sufficient distance from the edge of the old sole. This arrangement also assists in supporting the table 65 which is sometimes broken by wear of the awl and needle and subsequent downward blows or pressure of the needle, awl and presser-foot.

In the accompanying drawing Figure 1 is 70 a front elevation of such parts of a shoe-sewing machine as is necessary to the understanding of my invention, showing the guard attached to the adjustable edge-gage, and the work-supporting table; Fig. 2, a 75 right-side elevation of said table and guard and adjacent parts; Fig. 3, a front elevation of the table showing the guard let into the work-receiving end of the table; Fig. 4, a plan of the table recessed at the work-receiving end to admit the guard; Fig. 5, a 80 plan of the table shown in Fig. 1; Fig. 6, a front elevation of the table shown in Fig. 4; Fig. 7, a front elevation of the table shown in Figs. 1 and 5; Fig. 8, a plan of 85 the guard adapted to be used with the table shown in Figs. 4 and 5; Fig. 9, a front elevation of a modification of the table and guard; Fig. 10, a plan of a modified guard and Fig. 11, a front elevation of a table 90 adapted to be used with the guard shown in Fig. 10; Fig. 12, a front elevation of a table and guard formed integrally with each other showing also the presser-foot and edge-gage. 95

A indicates a part of the frame of the machine; B, the work-supporting table; b, the slot which serves as a passage for the needle and thread and awl; C, the edge-gage; c, the stand which supports the edge-gage and is adjustable to vary the distance 100 of the stitches from the upper of the shoe; D, the presser-foot; d, its holder; E, the awl; all these parts, except the table, as hereinafter explained, being of the usual construction and operation as shown in said 105 previous patent.

In sewing the out-sole to the welt in a machine of the class to which this invention relates, the work is inverted and the projecting part of the welt rests upon the table 110

B. The guard, G, formed of material capable of resisting friction and wear of the shoe-upper, preferably, of spring sheet-steel extends beyond the ends of the needle-slot b 5 and below the table B far enough to protect the shoe-upper and the fingers of the operator from the awl and needle of the machine, and is, or may be shaped and supported as described in said previous patent, except 10 that the upper edge g^1 of the head g in front of the table instead of being thinned to avoid increasing the minimum distance of the shoe-upper from the needle and awl, that is from the row of stitches which unite 15 the outsole and the welt,—is let into the front of the table beyond the ends of the needle-slot b, the intermediate part of said upper edge g^1 being cut away to avoid the necessity of thinning the comparatively 20 weak front wall of said needle-slot and to bear upward against and to support said front wall. The front of the head g and of the table B are shaped to form a smooth and practically continuous bearing surface for 25 the shoe-upper. The incline g^2 may be let into the pointed or rounded work-receiving end b^1 of the table B, the upper surface of the table being recessed at b^2 (Figs. 3, 4 and 30 6) to receive said incline, but this is not necessary as the work passes over the incline on to the table and the incline may be as shown in said patent and in Figs. 1, 5 and 7 of the accompanying drawing.

35 Of the modifications, Fig. 9 shows that the bearing parts g^3 b^3 of the head g and table B may be straight; Figs. 10 and 11

show, that the upper edge of the guard may be bent over backward at g^4 to fit a corresponding groove b^4 in the table; Fig. 12 shows that the guard and table may be integral with each other.

I claim as my invention:

1. In a shoe-sewing machine in combination, a work-supporting table having a needle-slot and a recess in its front work-engaging face, and a guard extending below said table, said guard having its upper edge portion received in said recess. 45

2. In a shoe-sewing machine in combination, a work-supporting table having a needle-slot and having a recess between said slot and the work-receiving end of said table, and a guard extending below said table, said guard having its upper edge portion received in said recess. 50

55 3. In a shoe-sewing machine in combination, a work-supporting table having a needle-slot and a guard extending below said table and having its upper outer surface continuous with the front surface of said table. 60

4. In a shoe-sewing machine in combination, a work-supporting table and a guard having an incline to extend over the work-receiving end of said table, said guard and table having continuous front surfaces. 65

In witness whereof, I have affixed my signature in presence of two witnesses.

GEORGE ELI MONGEAU.
